UNITED STATES PATENT OFFICE.

CHARLES C. HANSEN, OF NEW YORK, N. Y., ASSIGNOR TO THERMAL APPLIANCE COMPANY, INC., A CORPORATION OF NEW YORK.

WATER-HEATER AND REGULATOR THEREFOR.

1,209,836.

Specification of Letters Patent. Patented Dec. 26, 1916.

Application filed May 6, 1915. Serial No. 26,274.

To all whom it may concern:

Be it known that I, CHARLES C. HANSEN, a citizen of the United States, residing at New York city, borough of Manhattan, in the county of New York and State of New York, have invented new and useful Improvements in Water-Heaters and Regulators Therefor, of which the following is a specification.

10 My invention relates to new and useful improvements in water heaters and particularly of that character or type adapted to be interposed in a circulatory water heating system, and wherein means is provided 15 for heating the water by live steam either from a boiler or other suitable source, or with exhaust steam.

20 My invention contemplates an improved and simplified construction of the water heater, and also improved and simplified means for controlling the supply of steam to the heater, so as to regulate the temperature to which the water is heated and for maintaining the water at or about the desired temperature, the invention being an improvement upon the devices illustrated 25 in patent to Madsen, No. 940,980 of November 23, 1909, and Kibby, No. 1,018,711 of February 27, 1912.

30 The invention consists in the improvements to be more fully described hereinafter, and the novelty of which will be more particularly pointed out and distinctly claimed.

35 I fully and clearly illustrate my invention in the accompanying drawings, to be taken as a part of this specification, and wherein:

Figure 1 is a plan view of one end of a preferred embodiment of my invention. 40 Fig. 2 is a plan view of the opposite end of the heater from that shown in Fig. 1. Fig. 3 is a longitudinal section through the heater on the line 3—3 of Fig. 1. Fig. 4 is a longitudinal sectional view through the 45 heater taken on the line 4—4 of Fig. 1, and at right angles to the section of Fig. 3. Fig. 5 is a detail view of a coupling or connection employed with one of the water pipes. Fig. 6 is a section on the line 6—6 of Fig. 5.

50 Referring to the drawings by characters of reference, A, B, designate, respectively, end headers, the former being preferably used as the inlet and outlet header for both steam and water, as hereinafter described.

55 The header A is substantially rectangular in

construction, consisting of an outer end wall 1, an inner end wall 2, and a rectangular surrounding side wall 3, thereby forming a rectangular chamber. The chamber of the header is divided by a transverse partition 60 4 into an outer water-receiving chamber and an inner steam chamber. These outer and inner chambers are each divided by two transverse partitions 7, 8, into independent sets of chambers adapted to provide respectively for circulation of the water and steam, as will be hereinafter set forth, there being a water inlet chamber 5, an intermediate water chamber 5^a and a water outlet chamber 5^b, a steam inlet chamber 6, an intermediate chamber 6^a and a steam outlet chamber 6^b. The end wall 1 of the header A is preferably removable so as to permit access to the interior of the header, said wall being secured in position by bolts 9 projected 75 through said end wall through a flange 3^a on the surrounding side wall 3 of the header, and by bolts 9^a threaded into said partitions 7 and 8. Steam enters the steam chamber 6 through an inlet 10, controlled by a valve 80 10^a, and leaves said outlet chamber 6^b through the outlet 11. Water enters the water chamber 5 through the inlet 12 and, after circulating through the system, as will be hereinafter described, leaves the outlet 85 chamber 5^b through the outlet 13.

The header B consists of an inner end wall 14 and an outer end wall 15, together with a surrounding side wall 16, forming a substantially rectangular chamber within 90 the header. The chamber within the header is divided by a transverse partition 17 into an inner chamber for steam and an outer chamber for water, said chambers being further divided by a partition 18 into 95 separate water chambers 19, 19^a, and steam chambers 20, 20^a, said partition 18 extending at right angles to the partition 17. The end wall 15 is preferably removable, and is secured in place by bolts 21 engaging a 100 flange 22 on the header, and by bolts 23 threaded into the partition 18. The inner walls 2 and 14 of the respective headers are connected by a plurality of steam pipes or conduits 24, the ends of which are expanded 105 or threaded into openings in said end walls, or otherwise secured to the latter, so that communication is established between the three steam chambers 6, 6^a, 6^b, at the inner portion of the header A with the two steam 110

chambers 20, 20^a, at the inner portion of the header B, as will be described. In the embodiment shown there are preferably eight of these steam pipes arranged in four pairs, and the arrangement is such that steam entering the chamber 6 through the inlet 10, will flow through two of the pipes 24 into the chamber 20, thence out of the chamber 20 through another pair of steam pipes into the intermediate steam chamber 6^a in the header A, whence the steam flows out through a pair of said pipes 24 into the chamber 20^a, from which chamber it flows into the remaining pair of pipes and through the same into the outlet chamber 6^b in the header A, which communicates with the outlet 11. It will be seen that the arrangement is such that the steam flows back and forth through the alternate pairs of pipes. Extending through each of the pipes 24 is a water pipe 25, said pipes 25 being of an exterior diameter less than the interior diameter of the pipes 24, whereby a concentric space for the flow of the steam is provided between each steam pipe and its contained water pipe, as indicated at 26. The ends of said water-conducting pipes extend beyond the ends of the steam pipes 25, across the steam chambers of the headers, and through the partitions or diaphragms 4 and 17, respectively, in the headers, so that the open ends of said pipes will communicate with the water chambers in the headers in order that water may circulate from one header to the other and be heated by the steam flowing through the pipes 24 and surrounding the water pipes. The water pipes connecting the chamber 19^a with the inlet water chamber 5 and the intermediate water chamber 5^a. I preferably fix at one end to the partition 17 by any suitable connection, as by threading the ends of said pipes and securing them in place in openings in said partition by jam nuts 26 on opposite sides of said partition, while the opposite ends of said pipes slidably project through openings in the partition 4, suitable packing 27 preventing leakage at this point. The other pair of water pipes connecting the chamber 19 with the intermediate water chamber 5^a in the header A are secured in place in the same manner as that already described for the other water pipes, but the remaining two pipes connecting the water outlet chamber 5^b with the chamber 19 are connected to the respective headers in a different manner, in order that they may be employed to control the valve 10^a, as will now be described. One of the last two tubes—that is, the ones connecting the water outlet chamber 5^b with the chamber 19 in the header B, has one end anchored to the end partition 15 of the header B, so as to be rigidly connected to said end wall. This connection preferably consists of a socket

piece 28 having a threaded socket to receive the threaded end 29 of the water pipe, said socket having an opening through the wall of the socket piece, as at 30, so that communication is afforded between the end of the water pipe and the chamber 19. The socket piece is provided with a threaded shank 31 and a shoulder 32, said shank extending through an opening in the plate 15 and being engaged by a clamping nut 33 for securing the socket piece to the end wall, the latter being clamped between the shoulder 32 and said nut. The opposite end portion of this pipe extends slidably through a suitably packed opening 34 in the partition 4 in the header A, and the end of said pipe is threaded, as at 35, into a threaded socket in the end of a socket piece 36 located in the water outlet chamber, said socket piece having an opening 37 communicating with the pipe so that communication is established between said pipe and the water outlet chamber. The socket piece is provided with an extension plunger rod 38 passing slidably through an opening 39 in the end plate 1 of the header A, the space between said extension and the wall of the opening in said plate being packed by any suitable packing 40. The other water pipe connecting the water outlet chamber 5^b in the header A with the chamber 19 in the header B has one end connected to the end plate 1 in the same manner as the end of the other water pipe is connected to the end plate 15 of the opposite header, and is provided with a socket piece located in the chamber 19 and an extension rod projecting outside of said chamber in the same manner as described for the first pipe.

By the arrangement shown it will be seen when the controlling pipes are heated that any expansion resulting from said heating will cause said pipes to move longitudinally in opposite directions. Connected to the extension member 38, which projects through the wall 15, is a cross bar 41 rigidly connected to the outer end of said extension rod by jam nuts 42 on opposite sides of said cross bar and threaded on said extension rod, as shown, but it will be understood that any other means may be employed for this purpose. Connected to the opposite ends of said bar 41 are the ends of connecting rods 43, the ends of the latter opposite to those connected to the rod 41, being each connected to the intermediate portion of a cross bar or plate 44 on each side of the apparatus. The rods 43 may be guided through suitable openings 45 in the flanges 22 on the shell of the header B. Connected to each cross piece 44, on opposite sides of the rod 43, are rods 46, the opposite ends of which project beyond the end wall 1 of the header A, and are connected to the opposite ends of a cross bar 47.

- It will be seen that the expansion and contraction of the pipe 25 to which the cross piece 41 is connected will serve to move the rods 43 longitudinally, carrying the bar 47 with them. The extension rod 38 connected to the other controlling pipe opening into the water outlet chamber 5^b, is pivotally connected, as at 49, to one end of a lever 50, the opposite end of which is pivotally connected, as at 51, to the valve stem 52 of the valve 10^a for controlling the flow of steam to the steam inlet chamber in the header A. The lever 50 is slotted, as at 53, to receive a fulcrum pin 54 mounted in the upper portion of a fulcrum block 55, which block is mounted for adjustment lengthwise of the bar 47 and the slot 53, said block being provided with a shank 56 extending through a slot 57 extending longitudinally of the bar 47, said block being held in adjusted position by a clamping nut 58 engaging said shank. I preferably provide either the lever 50 or the bar 47 with indications, as shown on the lever 50, to assist in adjusting the fulcrum block at the proper point to cause the valve to be opened or closed to maintain such a supply of steam to the valve as to result in the desired temperature of the water flowing through the pipes 24.
- In order to prevent bending of the connecting rods 43, 43, and preserve them in parallelism so that they will pull equally and evenly, I may provide an intermediate brace or guiding member, consisting of a plate 59 clamped to the steam pipes 24 by means of a bolt 60 and clamping plate 61, the ends of said plate 59 having openings 62 through which said connecting rods 42 extend.
- The construction being as above described, the operation of the invention may be briefly stated as follows: The water inlet 12 to the chamber 5 is connected with a suitable water supply, or with one end of a circulatory system, and the outlet 13 is connected to a discharge, or to the other end of the circulatory system, and the steam inlet 10 to the chamber 6, and the valve controlling the same are connected to a suitable source of steam, either alive or exhaust. When the water is supplied to the inlet chamber 5 it flows into the first pair of pipes 25 and through said pipes and out of the opposite ends thereof into the chamber 19^a, whence it flows back through the next pair of water pipes 25 into the intermediate water chamber 5^a in the header A. From this intermediate chamber the water flows down the next pair of pipes into the chamber 19. From the chamber 19 the water flows through the openings 30 in the socket-pieces 28 into the last pair of pipes 25, constituting the controlling pipes, and flows through these pipes and out of the orifices 37 in the socket-pieces 36, into the water outlet chamber 5^b, whence it passes out through the outlet 13. The steam flowing in through the inlet chamber 6 flows down the steam pipes connecting the same with the chamber 20, and out of said chamber by way of the next pair of steam pipes into the intermediate steam chamber 6^a in the header A, whence it flows out through the third pair of steam pipes into the chamber 20^a, and then out through the last pair of steam pipes into the steam outlet chamber 6^b, thus heating the water pipes contained in the steam pipes and the water therein. The steam leaves the chamber 6^b through the outlet 11.
- It will be apparent that as soon as the controlling water pipes connecting the water inlet chamber with the chamber 19 become heated they will expand lengthwise, the expansion of one pipe taking place solely in one direction, while the expansion of the other pipe takes place solely in the opposite direction. This expansion movement moves the rods 43 in one direction, while the rear end of the lever 50 is moved in the opposite direction, so that the lever 50 will be swung on its fulcrum to regulate the valve to thereby maintain the desired temperature of the water flowing through the heater. By employing the oppositely movable expansion tubes, I am enabled to provide an extremely sensitive controlling mechanism, because the combined expansion of said tubes taking place in opposite directions will result in the valve being operated promptly upon but slight changes in temperature of the water.
- It will be understood that the controlling mechanism is sensitive because the degree of expansion of the tubes possible in a given temperature of the water is multiplied in effect. Thus, if the expansion of tube 25 is sufficient to move valve stem 52 one-quarter of an inch, the tube 25 likewise expanding to the same degree, will add a corresponding movement to the valve stem, and of course a fall in temperature will reverse the action of the tubes. Thus, by the multiplying action of the controlling mechanism upon the degree of expansion to which the water pipes are subjected, very slight changes in the temperature of the water will effect substantial movements of the valve stem.
- I may, and preferably do, place filtering material, such as mineral wool or other material suitable to the purpose, in the water chamber, or any of them, to filter the water as it flows through the heater, as shown in the chambers 5, 5^a, and 19^a.
- What I claim and desire to secure by Letters Patent of the United States is:
1. A water heater comprising spaced headers, each header having separate chambers, steam pipes connecting a chamber of one header with a chamber of the other

header, water pipes extending through said steam pipes and having their opposite ends opening into the other chamber of said headers, a valve controlling the admission of 5 steam into one of said headers whereby the water pipes may be subjected to expansion, a lever for operating the valve, a connection between said lever and a water pipe whereby the said expansion may actuate the lever, 10 and means including a second water pipe for multiplying the effect of said expansion upon the lever.

2. A water heater comprising spaced headers each divided by a diaphragm into 15 separate chambers, steam pipes connecting a chamber of one header with the corresponding chamber of the other header, water pipes extending through said steam pipes and said diaphragms, one of said water pipes having 20 one end fixed to an end wall of one header and the opposite end projecting slidably through the end wall of the other header, a second water pipe extending through one of said steam pipes and having one end anchored in the end wall of said other header 25 and projecting through the end wall of the header to which said first-named water pipe is anchored, a valve controlling flow to said steam pipes, a lever for operating said valve 30 and having one end connected to the slidable end of one of said water pipes and connections between the slidable end of said other water pipe and said lever, whereby relative movement of said water pipes due to expansion 35 and contraction multiplies the effect of each pipe to operate said valve.

3. In a water heater, spaced headers each separated by a diaphragm into a steam chamber and a water chamber, steam pipes 40 connecting the steam chambers of said headers and fixed to a wall thereof, water pipes extending through said steam pipes, steam chambers and diaphragms, and opening at their ends into said water chambers, means 45 for anchoring the end of one water pipe to the end wall of one header, and the end of another water pipe to an end wall of the other header, the opposite ends of said water pipes carrying thrust rods freely slidable 50 through the end walls of the opposite header from that to which said pipes are anchored, respectively, a valve for controlling flow to one of said headers, and means actuated by the relative movement of said water pipes 55 due to expansion and contraction to operate said valve.

4. A water heater comprising spaced headers, each header being sub-divided into steam chambers, steam pipes secured in the walls of said headers and said pipes and 60 chambers alternating in serial connection for the serial flow of steam therethrough, each header being further sub-divided into water chambers, water pipes mounted in the walls of said headers, said water pipes and 65 said water chambers alternating in serial connection for the serial flow of water therethrough, said water pipes extending through the steam chambers and steam pipes whereby the water is heated, a valve for controlling the flow of steam through the steam chambers and pipes, controlling members connected with said valve and subjected to the temperature of the water flowing 70 through the water pipes to be expanded or contracted, and means for causing the expansion and contraction of one of said members to be added to the expansion or contraction of the other member whereby to multiply the power and range of adjustment 75 and control of said valve.

5. A water heater comprising spaced headers, each header being sub-divided into steam chambers, steam pipes secured in the walls of said headers and said pipes and 80 chambers alternating in serial connection for the serial flow of steam therethrough, each header being further sub-divided into water chambers, water pipes mounted in the walls of said headers, said water pipes and 85 said water chambers alternating in serial connection for the serial flow of water therethrough, said water pipes extending through the steam chambers and steam pipes whereby the water is heated, a valve for controlling the flow of steam through the steam chambers and pipes, said water pipes being 90 free to expand and some of said water pipes being connected with said valve to effect control thereof by their expansion or contraction, and means for causing the expansion or contraction of said pipes to be added whereby to multiply the power and distance 95 of adjustment of said valve.

In testimony whereof I have hereunto 100 signed my name in the presence of two subscribing witnesses.

CHARLES C. HANSEN.
